SUPPORTING DEVICE

George T. Mott, Pearl River, N. Y.

Application April 14, 1936, Serial No. 74,259

10 Claims. (Cl. 155—58)

This invention relates to supporting dynamic mechanism, suspended from and in relation to: a fixed, stationary framework, said mechanism; providing for a glide oscillating action, freely floating, and untrammelled within its operating throw limits, and with an included, self-contained, gravity return power phase, in association with a suspended, oscillating cradle element, so designed: as to carry a load, and wherein 5 by said cradle operates in the horizontal, or in close approximation thereto, and in greater length of travel, than the actual length of the suspended supporting levers, and wherein said 10 oscillating action may be performed thru resilient, tentering contacts whereby; the initially required power demand shall at the point of application be reduced to a comparative minimum, and the developed internal dynamic stresses shall be equalized, whereby; the action is in 15 smooth continuity, and free from terminal shock and chatter, while continuing in operation under the influence of power conservation, and is thereby especially adaptable to domestic swings, porch and de-luxe gliders and other personal 20 usage devices and the industrial arts as adjustable thereto.

An object of the invention is to provide therein, an action similar to that, of a freely swung element, as when suspended from an upper structure, such as a common fulcrum but where in this application, the customary triangular plot of said swing element, is truncated, but at an angular relationship to the horizontal and at any predetermined point, and the upper structure 35 above said truncated line is thereafter eliminated.

An important object of the invention is to provide within said action, a throw length in the cradle-support, materially in excess of the 40 actual length of the suspended, supporting means.

An additional functional object of applicant's mechanism, is to provide in a supporting device of alternate concave and convex supporting surfaces, such action as to free the device, while freely floating from the customary distressing, inertia terminal shock, incident to a swing action, as in known gliders and other suspended devices, and as evident at the conclusion of each 50 swing oscillation, and to substitute therefore, a resilient, vibrant, tentering freely floating terminal action of such mechanical delicacy, as to be imperceptible in relation to shock effect.

A further object is to so poise the load weight 55 in angular relation to the horizontal, as to pre-

determine the load lift, and the consequent initial power demand, and the subsequent gravity effect in relation to the measures of power conservation, while retaining a smooth, vibrant, tentering action, with a terminal advance in repose, beyond the customary center of gravity as evidenced by a vertical position of the supporting levers.

Further and of major importance, is the object contained in the means employed for power 10 conservation, (generally muscular) thru the inclusion of variables in the leverage relations of the several elements employed, and of variable means in connection with alternate concave and convex contact surfaces, whereby, said muscular effort in its power application and in comparison with the known art is relatively at a very low power tension and provides means to eliminate fatigue.

A prime subject of importance, is indicated 20 in the means included to preserve a dynamic equilibrium within the developed power stresses and further thereby preserve thru the same measures the mechanical integrity thereof.

A further and basic object, is included in the 25 mechanism, wherein are provided measures of resilience against the customary terminal shock effect, and to absorb the recoil in power conversion against the inertia incident to a change of direction and without chattering effect.

A most important object of the invention is in 30 the application of said floating-glide mechanism to say: a so-called porch glider, a garden type or child's swing, to a floating de-luxe comfort or rest chair, or similar devices operated by muscular effort, generally pedal, wherein is the assured, comparative minimum power effect desired thru the inclusion of the power conservation measures, as amplified hereinafter.

A desirable object is further included in the 35 mechanism for any predetermined adjustment in the throw or in power tension and which makes possible the maintenance of the throw in the horizontal or in close approximation thereto and thereby the application of the floating-glide principle to a comfort or rest device or to gymnastic 40 purposes, and likewise the incorporation into service for automobile and train seats, and it is this possible variable relationship of constituent parts which also provides for the adjustment level and pitch of an individual seat element, and which makes the mechanism also adaptable to 45 industrial purposes.

In the accompanying drawings, which are referred to herein, and form part hereof, are sev- 50 55

eral illustrations, setting forth certain principles of the invention, and therein are shown, several embodiments of the invention as applied to gliding-floating, supporting devices.

5 Of the drawings:

Fig. 1 is a front elevation of the device in its simplest form—employing but a single unit of the invention and as applied, in this instance to a child's swing.

10 Fig. 2 is a side elevation in detail of Fig. 1.

Fig. 3 is a top view in plan, of Fig. 1, showing the basic supporting member for this type.

15 Fig. 4 is diagrammatic, showing the means of plotting the mathematics, and the dynamics thereof.

Fig. 5 shows an end elevation of Fig. 1, in part, showing in line, a supporting element, but as applied to so-called porch type gliders, with a low swing head, and showing also, an alternate means 20 of cradle support in substitution for a normal two unit end, but where a second unit is shown in association and in phantom.

Fig. 6 is a plan view of Fig. 1, showing one end 25 with its load-supporting surfaces and supporting structure.

Fig. 7 is a complete view in perspective, of a four unit device, in accord with the principles outlined, and as applied to single or multiple seat units, is shown in the preferred form.

30 Fig. 8 is a sectional elevation on the line 8—8 of Fig. 5, showing in side elevation the construction of a single floating member mounted on its suspension frame and including the companion integrity element.

35 Fig. 9 is a sectional elevation on the line 9—9 of Fig. 5, showing a floating unit in full line with an additional unit of a floating member in phantom but with an auxiliary load supporting device, employed specifically, when but one floating lever 40 is desired.

Parts of Fig. 9 are broken away.

Fig. 10 shows alternate means for effecting the variable leverage relationship, with its resultant power conservation for effecting the minimum 45 required power application in the floating-glide action.

Fig. 11 is another means of effecting power conservation by varying the lengths in the respective lever parts and thus varying the leverage differential, and this is especially adaptable when an extremely low power demand is desirable, and is a 50 preferential means when applied to comfort and domestic, low tension devices, as operated by muscular effort.

55 Referring now to the drawings in detail and first to Figs. 1, 2, 3 wherein is illustrated a gliding-floating oscillating device in accordance with the principles contained herein, said device operating in this instance, as a cradle, a swing, or 60 a glide support, and wherein said cradle is maintained in the horizontal or in close approximation thereto.

In the figures noted, the objects of the invention as previously outlined are fully contained, 65 and as applied say, to a child's swing.

In a swing of the current art, the suspending element describes an arc incident to its pendulum throw, and dependent on an obligatory height, thereby raising the occupant a variable distance 70 above the horizontal and because of this height, demanding a comparatively heavy power application and also endangering life and limb in the event of a fall therefrom, said pendulum action also causes many persons to become distressingly ill.

In the instant invention, the swing action is in glide effect and while not restricted as to its length of plotted throw, constantly maintains the horizontal as related to the floor level or remains in close approximation to said horizontal. 5

Referring to the drawings in detail, and again to Figs. 1, 2, 3, wherein is shown means comprising a frame member suitable to a load supporting device, and sustaining a supporting member 6, from which member the operating unit is suspended thru the load supporting surfaces 8—9 and their contact bolts 7—7a.

Said operating unit, Figs. 1, 2, 3, consists of load supporting surfaces 8—9 including alternate concave and convex surfaces in preferably continuous convolutions, said supporting surfaces 8—9, and further set in combination in angular relation to the horizontal, and including a load carrying leverage device 20, with arm members 11—12 projecting from said lever and contacting said surfaces 8—9 and arranged to oscillate thereon.

The device is shown to effect the same swing action, as that of an element suspended from an elevated fulcrum, but that thru the angular relation of the combined surfaces 8—9, and in relation to the horizontal, there is effected a truncating of the triangle of pendulum swing, but in said angular position, and the load travels in the horizontal or in close approximation thereto, 30 while power conservation is effected in the provision for limiting the load lift thru angular relation.

It is by reason of the angular relation of the load supporting elements 8—9 and by further reason of the truncating of the triangle of pendulum swing, that the center of gravity of the load in repose, does not conform to the initial vertical center line of the upper structure, when said line is drawn thru the intersection of the 40 conforming lines of the lever 20 as projected from the extreme throw limits of said lever 20, and it is in the predetermined differential in angular load supporting means 8—9, or the pitch thereof, which provides for the relative ease of 45 operation and the conservation in power application, and the regulation for any desired degree of power application.

It is in the continuation of said load supports 8—9 into the concave formation shown, toward 50 the extremities of throw of said lever 20 wherein resides the property of resilience against the customary terminal shock.

It is in the continuation of the load supports 8—9 into the concave terminal formation and 55 at the junction of said concave formation with the convex formation wherein resides the vibrant, tentering action at the said point of contact shown by the number 8 of Fig. 2, and where 60 said tentering action, at the verge of either direction, absorbs the inertia effect, and assists in combination with the variable relations in the load carrying lever 20, to effect power conservation, said power conservation consisting of a 65 reduction in the power required to operate said device when compared with the art.

At the conclusion of each said terminal throw as shown in the diagram Fig. 4, there is also effected by reason of the said upturned concave 70 faces of the contact element 8—9 and the angular relationship to the horizontal of the said element 8—9 an automatic impulse in the return throw action and without the immediate application of power.

When the instant initial action in the return of the load cradle has been accomplished thru the mediums of the said continuing concave formation of the supporting elements 8-9, and further to said load supporting members 8-9 being poised in angular relation to the horizontal, but little additional power is required to continue the throw in either direction, as the reaction has been absorbed in applied power, and this also assists in power conservation.

The concave and convex surfaces of the load carrying means 8-9 are preferably, as shown, in continuous association to restrict the device to compact dimensions.

It has been found, that, where the load supporting means 8-9, Fig. 2 are in alternate, concave and convex formation, there appear at the junctions of said concave and convex formation, tentative flat spots, which temporarily impedes the smooth and continuous operation of the device, as for instance; when the roller 14a of Fig. 2, is in load carrying contact at the identical point; where the roller 14a is shown in Fig. 2, on the supporting member 9, and the roller 13a correspondingly at the low throw point on the member 8. When the last phase of power conservation is desired the lever Fig. 11 can be used to advantage.

In the inclusion of Fig. 11, the short arm 12b, is set facing the power throw, or at the lower end of the hypothetical inclined line Fig. 2, on which line the load supports 8-9 are poised.

When substituting the lever of Fig. 11 for the lever 20, in Fig. 2, and when the contact pulley 14a is in the identical position shown in said Fig. 2, then the substituted lever 20a, in association with said inclined line of support will be in a forward position much in advance of that shown initially in Fig. 2, and a most desirable position from which to apply the initial backward impulse, with its power conservation, and of great importance, when it is especially desirable that the impulse power be very low. In a high swing element, however, this power may be incidental, but in a comfort device, becomes imperative in its lowest power application.

Again when the lever, Fig. 11, has been substituted for the lever 20, of Fig. 2, it is found that in the relative shortening of the arm 12, Fig. 2, by the substitution of the arm 12b of Fig. 11, and in conjunction with the suspended lever 20, and the inclined relationship of the contacts 8-9, there is included a load-power leverage differential when the power is applied at the point of load support, and which reduces thereby the measure of initial power demand thru an effective load lifting capacity which may equal in efficiency that of a pinch bar, thereby effecting the desired minimum in power demand and with included measures for an easy, smooth, shockless gravity return, as applied to the inclined supporting means.

When Fig. 11, with said variables in the relative length of the arms 11b-12b or equivalent variables in the diameters of the roller contact members, is incorporated in Fig. 2 in substitution for the lever 20, the leverage relationship is highly accentuated, and the means for load power conservation thus evidenced in the impelling muscular effort.

In the embodiment of the drawings is further shown the means relating to the retained mechanical integrity of the device.

When the load carrying lever 20, and its associate contact member 13a-14a are supported upon

the load carrying members 8-9, there is a marked tendency when the power is suddenly or unequally applied to derange the entire mechanism.

To obviate any such possibility of derangement, a companion power integrity member 26-26 is employed, said integrity member being also suspended from the basic support 6, Fig. 3 by bolted means 15-15a, wherein, said members preserve not only the mechanical integrity but primarily maintain the internal power stresses in constant equilibrium.

The element 26-26, suspended from a fixed, stationary supporting member, 6, is shown in plotted, companion association with the load supporting element 8-9, said load supporting element 8-9, shown in concave and convex formation, whereon the contact elements 14-15, of the load carrying lever 20 oscillates.

The said companion element 26 placed in remote relation to the said load supporting element 8-9, is associated in peculiar, related conformation, and in further connection with a given contact point 25a, and wherein said point 25a, is remotely located on the said freely swung load supporting lever 20, said point oscillating in close contact with the said element 26-26.

The contact points 14-15 and 25a, are formed in equi-angular relation on the freely suspended, load carrying means, wherein said points 14-15-25a are retained, within hypothetical circular contact relation, and ride rotatively on said hypothetical circle, moving also in oscillation on the said load supporting elements 8-9, whereby the initial stresses, incident to imposed power application, are maintained in dynamic equilibrium, as when the power is spontaneously applied against the remote point of load impingement 21, and by muscular effect, and in such tension as may be determined by personal mood.

Said equi-angular relationship in the contact point 14-15-25a, provides further for the retained augmented throw in the lever 20, wherein the load carrying cradle 21, suspended on said load carrying lever 20 is carried in horizontal throw, or in close approximation thereto, in greater distance than the actual length of said load carrying lever 20.

The aforesaid load supporting members 8-9, arise outwardly and in alternate concave and convex formation and from a common concave section thereof, (contact point 13 Fig. 2) develops thereafter, in continuation into convex surfaces in each direction, said load supporting members being further transformed into additional, continuing terminal surfaces in each instance, and said terminal surfaces set concave to the angular line on which said supporting load surfaces are poised in their divergent relationship and their further combined relation, to the horizontal, thereby containing said supporting surfaces 8-9 alternately concave and convex in their angular determination.

It is in these concave continuations at the terminal of said load supporting members 8-9, wherein is contained the resilience against the terminal shock effect in the movement of the lever 20 and it is further in the relationship at the continuing contact points, where the terminal concave surface 8-9, is joined by the preceding convex surface thereof, that: the contact member (as 14a Fig. 2) and as mounted with said alternate concave and convex load supporting surfaces, is poised in tenting relationship thereto, whereby the customary recoil is absorbed in said tenting effect, and applied against the re- 75

turn throw in smooth continuing action, and it is thru this combination of alternate concave and convex surfaces that the said tentering effect is accomplished and without chattering and effects 5 means for shock elimination.

When a forwardly inclined load carrying lever, with lateral arms and contact members thereon is receding from its forward position of repose, under an applied power, it has been found, that 10 upon reaching the vertical and thereafter; there is a continued lessening in the leverage power application, and to preserve intact the measures of included power conservation, it is seen in the instant invention, that; when the said load carrying lever 20, has reached the vertical, the contact point 14a of said lever, will be in contact at the peak of the forward convex section of the load supporting element 8-9, and by reason of the close balance in the load-leverage relationship, 15 tentering thereon, riding thereby backwardly under the continued application of power and entering thereby upon the more precipitate, centrally disposed, concave section of the said load carrying element 8-9, whereby; the leverage effect in relation to the implied load is comparatively increased, and the actual power required to continue the throw to a position approximating the terminal thereof, is but slightly augmented and in a lesser ratio, than is shown for the length of 20 throw preceding the advent into the said centrally disposed concave section of said load supporting element 8-9, thus retaining the feature of power conservation.

In Figs. 1, 2, 3 is shown 21, a typical swing seat. 35 The diagram Fig. 4, is described substantially in the same manner as Figs. 1, 2, 3.

The respective load carrying members 8b-9b are shown mounted in angular relation to each other, and with the contact faces on the inside 40 of the angle within the intersecting lines which enclose the angle formed by the terminal throw lines of the lever 20a wherefrom they diverge, said supporting elements 8b-9b in combination, are also set in oblique, angular relation to the 45 horizontal, which horizontal is represented by the basic support line 6, Fig. 1.

The aforesaid integrity members 26-26 are also and independently adjustable to the oblique angularity of the combined supporting elements 50 8-9 and in companion relation thereto, assuring the continued integrity of the structure under any circumstances. See Fig. 2.

The mechanical action and the dynamics of the device are indicated in Fig. 4, wherein the 55 load supporting elements 8b-9b, with their alternate concave and convex surfaces are shown, and set in mean angular relationship to the horizontal.

In Fig. 4, is shown further the resilience of the 60 device, and wherein there are also included the concave continuing terminals of said supporting elements 8b-9b, and it is by reason of said included concave terminals, and the included associate elements therewith, wherein: is provided a resilience against the customary terminal shock effect, and whereby the impetus in the 65 recoil is absorbed in applied power against the inertia of the return throw.

Further; it is in the immediate relationship of 70 said continuing, concave and convex formations of said supporting element 8b-9b, and in coordination with the load carrying leverage device 20 and its associate arms 11a-12a that: at any given moment of effective operation the peak 75 load contact, incident to the direction of operation,

always corresponds with and is imposed upon, a curved peak of said load supporting surface 8b-9b and in tentering contact therewith, and is in position at all times to function instantaneously, relatively free from excess load impingement under the influence of gravity, and when operating in either direction, whereby the conservation of applied power is effected. 5

It has been found that within the imposed degree of angularity of said load supporting elements 8b-9b, resides the control of the power tension adjustment, which permits of operation, between that of comparatively negligible conserved power demand, when applied to comfort floating devices, and that of relatively heavy 15 power demand for gymnasium, or industrial service, and it is in said means of adjustable, angular relationship to said horizontal, wherein lies the power differential and the incident velocity of the cradle device in its gravity return to a normal 20 forward position of repose.

When the combinations of circumstances are such, with the included load supporting means 8b-9b, Fig. 4, in oblique angular relationship to the horizontal 6, and in such degree as to 25 induce the ease of operation effective in power conservation, or a low power application, and when the lever 20, Fig. 2 has completed its throw to the extreme left, and that in consequence thereof, the supported load is at its extreme 30 backward throw, and the supporting pulley 13a, Fig. 2, of the lever arm 11, is in the immediate element 35 point of contact application with the number 8 of Fig. 2, and said point 8 being the point of junction between the concave and convex bearing surfaces 8-9, Fig. 2, and when the lever 20, Fig. 2, begins its return throw to the right, it is found there is instituted a momentary, vibrant tentering action, at the said contact point 8 of Fig. 2, which tentering action operating in either direction absorbs 40 all inertia and tendency to shock effect and prevents chattering.

In Fig. 4, is further shown the means for increasing, at the point of load contact 21, the throw-length of the lever 20a, beyond that of the 45 actual length of the said suspending lever 20a, said suspending lever 20a, Fig. 4, with its load shown in contact at 21, when moving in either direction, right or left, floats upon the load supports 8-9, set as aforesaid in angular relation 50 to the horizontal, so that in the action of said lever 20a, and the cross-head 10 thereof, and thru the roller contacts 13a and 14a on said supporting contacts 8-9 shown in Fig. 2, the movement generally is an average movement parallel in effect 55 to the inclined line, on which said supporting means 8-9 are graphically mounted, and on which said load supporting elements 8-9 are poised, thereby extending the throw-length of the lever 20, at its included cradle load contact point 60 21, thru the augmented range of throw, included within the tentative length on the load supports 8-9, Fig. 2, and incident to the initial length of the included lever 20, and the leverage relationship within said lever and the arms 11b-12b 65 thereof, and whereof the load supporting end of the lever 20 continues in horizontal throw fully or in part thereof.

In the variation of the load supporting elements 8-9, from the horizontal, it is important, 70 that the load levels 20A-20A, be unequal in length, in the (tentative) same degree that the hypothetical line of the said load supports 8-9 initially varies from the horizontal, in which variation of length is an additional measure to 75

preserve a throw within limits in the horizontal and a maintained throw in close approximation to the horizontal.

Inasmuch as all operating measures are dependent only on the load supporting elements 8-9, the respective lengths in the lever 20a, exerts no influence whatsoever on the gravity effect or other measures excepting only the relation of the cradle to the horizontal.

10 Fig. 5 illustrates another means of effecting the floating-glide principle of this application, and is actually a modification of Fig. 7, inasmuch as parts are omitted and other parts substituted therefor, to effect a more economic structure. The description of this device in principle is substantially the same as that of the preceding figures.

In Fig. 5 a substantial frame work 5a is provided, on which frame work are mounted, the 20 load supporting members 8a-9a, thru the adjustable contact bolts 7-7a, said load supporting members 8a-9a, being alternately of concave and convex formation, with continuing terminals 8b-9b of concave formations said 25 terminal forming the means of resilience in the oscillations of the load contact elements 13a-14a on said load supporting members 8a-9a.

In further association with said load supporting elements 8a-9a, is the companion element 30 26, also in adjustable relationship to the said supporting element 8a-9a, and in further combination with the contact elements 13a-14a-25a, and in conjunction with the suspended load carrying lever 20a, and the cradle means 21a.

35 In this device of Fig. 5, the duplicate lever 20a, as seen in Fig. 7, and shown in phantom in Fig. 5, is omitted, as is also the associate load supporting means 8a-9a, and the duplicate companion element 26, and substituted for the 40 said omitted measures, is a companion element 26b, plotted as before in association with supporting means 8a-9a, but from the contact point 27, said point 27, being at the end of the cradle 21a, at which point said duplicate lever 45 is omitted, said companion element 26b, being in adjustable relation to the framework and to the horizontal or its plotted deviation therefrom.

50 Imposed upon the load carrying lever 20a, and at the load point 21, is, as previously noted, one end of the cradle 21a, and in pivotal relation to the load carrying lever 20a, the opposite end of said cradle 21a, is imposed upon and travels freely, on the companion element 26b, thru the contact element 27a, the impelling power being 55 supplied as before by muscular effort.

It will be seen, that the function of horizontal throw in main or in part may be observed in this device, and in connection with a free and untrammelled floating measure, and with the further measures of freedom from shock, and the means of resilience, as well as the ease of operation and the inherent power of gravity return throw.

A modification of the invention is shown in 65 Fig. 7, wherein is illustrated a supporting device, used in gliders as adapted to so-called porch types and further adaptable to service for extreme comfort in operation, and for highly refined surroundings.

70 In this modification, there is shown a suitable framework 5a, and imposed thereon are the load supporting members 8a-9a, 8a'-9a', each shown in alternate concave and convex formation, and in continuation and with concave terminals 8b-9b, and which in combination com-

prise the said load supporting elements, and are imposed on said frame work 5a, thru the bolted means 7, said bolted means being capable of any reasonable adjustment. It is in the concave terminals of the said load supporting elements 8-9 wherein the resilience in the contact, with the roller or pulley contact elements 13-14 occurs, and it is in the immediate point of junction, between the concave terminal continuations and the adjacent convex surface of said load supporting element, wherein occurs the tentering contact with the contact points 13-14 and where further the implied load thereon tenters on the verge of either direction and under the influence of gravity, that is when the cradle in Fig. 7, is at the moment of reverse from the position shown, Fig. 7, and with the power momentarily applied against the load carrying end of the lever 20a, the load will be found to tenter at the said point of peak juncture shown at 14 20 in said Fig. 7, and wherein occur the measures of power conservation.

Freely suspended on said load supporting elements 8-9, are the load carrying levers 20a, slidably engaged in oscillating with said load supporting elements thru the contact rollers or pulleys 13-14, of the arms 11-12, whereby the load carrying end of said lever 20a, oscillates in parallel throw, while the contact elements 13-14 of said lever 20a thru the cross-head 10 and the 30 extending arms 11-12 thereof, oscillate in the general direction of the parallel, but more in reference to the hypothetical angular line on which said load supporting elements 8-9 are poised, which angular line of load poise, determines the 35 power phases in operation, and preserves the smooth even floating-glide effect as well as pre-determining the velocity thereof.

At the point of applied load 21, is shown a journal or bearing, and engaging within same, fitted 40 shaft ends shown at 21-21 of Fig. 7, which shafts carry the immediate cradle structure 35-36 in oscillation.

Adjustably mounted and arranged to conform to the said load supporting element and in any variable relation, are the elements 26, said companion means 26 also suspended from said framework 5a.

From any given point on the load carrying lever 20a, is an included contact point, with its contact pulley 25.

It is from said contact point 25, in connection with the contact points 13-14, and when oscillating on the load supporting elements 8-9, wherein the curved relationship of the companion 55 members 26-26 is plotted.

As aforesaid the substitution of the lever 20a of Fig. 11 for the lever 20a of Fig. 7, accentuates the leverage differential and increases the ease of operation, thru power conservation.

In Fig. 6, is shown a framework member on which the "supporting device" is suspended, showing specifically one end of Fig. 7, and in plan view, wherein 5a is the means on which the element is actually impinged, thru the load supporting elements 8a-9a, 8b-9b, shown in staggered relation to condense the unit in compact form, and supporting respectively thereon, the contact elements 13-14, of the lever 20a, in their oscillating relation to the supporting element 65 70 8a-9a.

In Fig. 8, is shown an end elevation on the line 8-8 of Fig. 5, showing specifically the frame element 5a, the load supporting element, 8-9, with the contact element 14, of the load carrying lever 75

20a, suspended thereon, and in conjunction therewith, a companion element 26, and in further association the auxiliary companion means 26b.

In Fig. 9, is shown, an end elevation on the line 5 9—9 of Fig. 5, parts broken away and parts in phantom said parts in phantom being those omitted in Fig. 5, and wherein is shown in full lines, one of the supporting measures 8a—9a, as shown in staggered relation in Fig. 6, and where- 10 in are illustrated the said load supporting measures 8a—9a, with the adjustable bolted means 1a, and the contact means 14, of the lever 20a, the companion means 26, and the contact means therewith 25, of the said lever 20a.

15 In Fig. 11 is shown the variable leverage relationship, wherein, when the short arm 12b, of the lever 20a, is turned forward, or in the direction of and against the applied muscular power at the point of load support 21, the leverage differential will tend to exert an increase in the relative power relation at the contact point 14, and materially assist in power conservation.

It is believed, that applicant's device as fully set forth herein, is distinguished from the references, for while applicant's device does, incidentally, effect a maintained stability of the included mechanism, applicant's device does further, and primarily, stabilize in power equilibrium, the internal stresses developed within the 30 measures of applied power, as outlined herein.

The invention in its broader aspects is not limited to the precise constructions shown and described nor to the specific applications thereof.

I claim:

35 1. Supporting means for a freely suspended, floating mechanism, with included internal dynamic measures, and comprising a suitable framework, in combination with an included active load, said supporting means being developed in alternate concave and convex formation and said means further; being in adjustable, angular relationship to the horizontal, and rising upwardly and outwardly therefrom in either direction, and from a common intermediate concave section contained therein, and a load carrying lever device, suspended from said load supporting means, said lever constantly in free and untrammelled, floating relation to said supporting means and further provided with contact measures, whereby one end of said lever may oscillate over said concave and convex supporting means in unconfined, glide effect, limited only by the extreme terminals of said supporting means, and wherein; at the termination of a throw cycle, 50 the load carrying end of said lever, will, under an included, positive gravity effect, be projected to a position of repose forward of the vertical while the said load carrying end of said lever, freely functions in the horizontal.

60 2. Supporting means: for a freely suspended mechanism, with included internal dynamic measures, and comprising a suitable framework, in combination with an included active load, said supporting means being developed in alternate concave and convex formation, said means being further set in angular relation to the horizontal, and measures included whereby said supporting surfaces, in combination may be adjusted to a predetermined degree of angularity, and a load carrying lever device, suspended from said load supporting means, said lever constantly in free and untrammelled floating relation to said supporting means, and further provided with contact measures, whereby one end of said lever may 65 oscillate on said concave and convex supporting

means, in unconfined glide effect, while the load carrying end travels in the horizontal and whereby the degree of power demand, and the incident velocity in the angular, gravity return throw, may be predetermined, and thereby effect a degree of power conservation.

3. Supporting means; for a freely suspended, floating mechanism, with included internal dynamic measures, and comprising a suitable framework, in combination with an included active load, a said supporting means, being developed in alternate concave and convex formation, said means further; being in adjustable angular relation to the horizontal, and rising upwardly and outwardly in either direction therefrom, and also from a common intermediate concave section contained therein, and a load carrying lever device suspended from said load supporting means, said lever provided at one end with laterally extended arms, said lever further suspended, constantly in free and untrammelled, floating relation to said supporting means, and further, said lateral arms being provided with movable contacts, whereby said lever may oscillate on said supporting means, in unconfined, glide effect, 25 while traveling generally in the direction of the horizontal and the load carrying end of said lever, further functioning in the horizontal, and whereby further, the load carrying end of said lever, travels a distance in the horizontal, in 30 greater length than the actual length of said supporting lever, and free from a centrally disposed shock effect, and whereby at the conclusion of a throw cycle the load carrying lever will be 35 in a forward terminal position.

4. Supporting means: for a freely suspended floating mechanism, with included internal dynamic measures, and comprising a suitable framework, in combination with an included active load, a supporting means, said means being developed in alternate concave and convex formation, said means further, being in adjustable angular relation to said horizontal, and rising upwardly and outwardly in either direction therefrom, and from a common intermediate concave section 45 contained therein, and a load carrying lever device suspended from said load supporting means, said lever provided at one end with laterally extended arms, one of said arms, set against the applied power effect, being of lesser length than the companion arm, said lever further suspended, constantly in free and untrammelled, floating relation to said supporting means, and further said lateral arms being provided with movable contacts whereby said lever may oscillate on said 50 supporting means, in unconfined glide effect, while the load carrying end of said lever functions in the horizontal, and the load lifting capacity of the device, in its leverage differential provides for a minimized effort in muscular power application thereof, and effects thereby a measure 55 of power conservation.

5. A supporting means for a freely suspended, floating mechanism, with included internal dynamic measures, and comprising a suitable framework, in combination with an active load, said supporting means, being developed in alternate concave and convex formation, said means further; being in adjustable, angular relationship to the horizontal, and rising upwardly and outwardly therefrom, in either direction, and from a common intermediate concave section contained therein, and a load carrying lever device, suspended from said load supporting means, said lever constantly in free and untrammelled float-

ing relation to said supporting means, and further provided with contact measures, whereby one end of said lever may oscillate over said concave and convex supporting means, in uncon-
 5 fined glide effect, and wherein at the termination of a throw cycle, the load carrying end of said lever, will under an included, positive gravity effect, be projected to a forward position of re-
 10 pose, while the load carrying end of said lever, functions in the horizontal and the customary swing super-structure be truncated in angular relation to the horizontal, and at a level con-
 15 sistent with the height of said load supporting means as determined.

15. 6. Supporting means, for a freely suspended floating mechanism, with included internal dynamic measures, comprising a suitable framework, in combination with an included active load, a supporting means, said means, further
 20 being in adjustable angular relation to the horizontal, and rising upwardly and outwardly, there-
 25 from in either direction, and from a common intermediate concave section contained therein, and a load carrying lever device, suspended from
 30 said load supporting means, said lever constantly in free and untrammelled floating relation to said supporting means, said lever further provided with lateral arms, and contact means thereon, wherewith; said lever oscillates on said load
 35 supporting means, in unconfined glide effect, and a further contact point, plotted on said lever, in remote relation to said load supporting means, and poised in equi-angular relation with the contact points on said lateral arms and a further
 40 companion element plotted with the remote contact point on said lever, said companion stress element being in close engagement with said remote contact point, and where; the several contact points, are poised in equi-angular relation,
 45 whereby; said contact points are held in power equilibrium, and the load end of said lever operates in the horizontal.

7. Supporting means for a freely suspended, floating mechanism, with included internal dynamic measures, and comprising a suitable framework, in combination with an included active load, said supporting means, being developed in alternate concave and convex formation, the extremities of said supporting means being continued in further concave formation, and in either direction, and a load carrying lever device, suspended from said load supporting means, said lever constantly in free and untrammelled, floating relation to said supporting means, and provided with contact measures whereby one end of said lever, may oscillate over said concave and convex supporting surfaces, in a floating, resilient, tentering action, thereby absorbing the inertia in a change of direction and without recoil shock-effect, while
 50 the load carrying end of said lever operates in close approximation to the horizontal.

8. Supporting means for a freely suspended, floating mechanism, with included internal dynamic measures, and comprising a suitable framework, in combination with an included active load, said supporting means, being developed in alternate concave and convex formation and set in

angular relation to the horizontal, the extremities of said supporting means being continued in further concave formation, and in either direction, and load carrying lever devices, suspended from said load supporting means, said levers constantly in free and untrammelled, floating relation to said supporting means, and provided with contact measures whereby ends of said levers, may oscillate over said concave and convex supporting surfaces, in floating, resilient, tentering 10 action, thereby absorbing the inertia in the change of direction, and without recoil shock effect, while the load carrying ends of said levers, support a load carrying cradle element operating in close approximation to the horizontal. 15

9. Supporting means for a freely suspended, floating mechanism, with included internal dynamic measures, and comprising a suitable framework, in combination with an included active load, said supporting means, being developed in alternate concave and convex formation and set in, angular relation to the horizontal, the extremities of said supporting means being continued in further concave formation, and in either direction, and load carrying lever devices, sus- 20
 25 pended from said load supporting means, said levers constantly in free and untrammelled, floating relation to said supporting means, and provided with contact measures, whereby: ends of said levers, may oscillate over said concave and 30 convex supporting surfaces, in floating, resilient, tentering action, thereby absorbing the inertia in a change of direction and without recoil shock effect, while the load carrying ends of said levers support the oppositely disposed ends of a cradle 35 load carrying element while the laterally disposed ends of said cradle are carried on an auxiliary companion element, and said cradle traveling in the horizontal or approximately thereto and the device functions under power conser- 40 vation.

10. Supporting means, for a freely suspended floating mechanism, with included internal dynamic measures, said supporting means comprising a suitable framework, in combination with an active load, said load supporting means, being further developed in alternate concave and convex formation, and a load carrying lever device, suspended from said load supporting means, said lever constantly in free and untrammelled relationship to said supporting means, and said lever provided at one end with lateral arms, said arms further provided with contact measures thereon, and so arranged and proportioned in combination with said load supporting members, that when 55 said load supporting members are poised in angular relation, said contacting members shall engage and oscillate on said load supporting members, while the applied load in its leverage relationship is impinged upon said supporting means thru a floating, tentering contact action, and on the verge of either direction, whereby a phase of included power conservation is maintained, while the load supporting end of said lever travels in a horizontal, or in close approximation thereto. 60 65
